UNITED STATES PATENT OFFICE.

GEORGE WALKER AND EDWIN WALKER, OF HAMBURG, NEW YORK.

IMPROVEMENT IN MIDDLENS-PURIFIERS.

Specification forming part of Letters Patent No. 148,099, dated March 3, 1874; application filed January 7, 1874.

To all whom it may concern:

Be it known that we, GEORGE WALKER and EDWIN WALKER, both of Hamburg, in the county of Erie and State of New York, have invented certain Improvements in Middlens-Purifiers, of which the following is a specification:

Our invention consists in the novel construction and arrangement and operation of various devices in one machine, by which flour, middlings, and offal are separated and entirely freed from dust, fiber, and other impurities, ready for regrinding, all to be hereinafter explained.

In the drawings, Figure 1 is a central sectional view through the entire machine. Fig. 2 is side elevation; Fig. 3, perspective of the shaking hopper; Fig. 4, end elevation; Fig. 5, sectional view of opposite end; Fig. 6, top-plan view with cover or casing removed; Figs. 7 and 8, detail views.

A A is the outside frame-work, with supplementary pieces bolted to the frame to support the working machinery. B is the receiving-hopper, and is at the same time a distributing feeding-shaker. (See Figs. 3 and 6.) It is hung on links a a, (see Fig. 4,) and has an upward forward and downward backward motion imparted to it by a bell-crank or its equivalent, b, and connected to a crank-pin or an eccentric by a connecting-rod, c. Across the inside of this shoe is swung a hinged valve, d, Figs. 3 and 6, for spreading and leveling the middlings evenly across the shoe, by pressing on the same when the shoe is in motion. The end of this shoe is cut off at a long angle, to discharge the middlings in a wide, thin sheet. The bottom of the shoe, from the valve d to the edge, is corrugated parallel with its length and direction of motion, to prevent the stuff from sliding toward either side. C is a shaking separator, for the purpose of separating from the good stuff the offal before sifting or bolting, and occupying the middle portion of the machine. This operates in connection with a vacuum-blast from the fan D, and a revolving, disintegrating, cylindrical brush E, (see Figs. 1 and 8,) to be hereinafter described. The separator is constructed with outer walls or boards e and inner board e', with an air-space, f, between, and sliding gates or valves,

g g, to regulate the force of the air, (see Fig. 7,) and through which passages air is drawn from the lower part of the machine, for the purpose of conducting any dust that may separate from the middlings after sifting into the vacuum-chamber G above the upper separator. This vacuum-chamber G is formed of an inverted box or cover, with a valve, I, Fig. 1. By opening said valve, more or less air is admitted to the vacuum-chamber, and thereby the force of the air in the passages in the separator is graduated properly. There is also an adjustable valve, I', just under the cover of the box. By turning said valve more or less, the force of the air in the air-passage m and o is graduated. In the separator are arranged two series of level, or nearly level, shelves or steps, h and h³, the latter terminating in an inclined plane, j, which leads into the head of the sieve E, the former, h, terminating just over the brush. Another series of bent partitions, h¹ and h⁴, their upper part formed into level, or nearly level, shelves, are also arranged in the separator, the latter, h⁴, series terminating in an inclined plane, i, with an outwardly-opening valve, k, for the escape of the heavier parts of the offal. All these extend across the entire width of the separator between the inner wall e' e'. The openings m m', between steps h¹ and h⁴, diminish gradually in size from the bottom to the top, so that the draft of air may increase in velocity and strength as it ascends, for the purpose of more effectually carrying the heavier particles of offal up into the vacuum-chamber G above, where, by reason of the enlarged space, and consequent diminished motion of the air, the denser particles fall onto the shelves h¹ h⁴ over the passages m and m', and by the peculiar shaking motion of the separator they are carried forward and precipitated down the inclined plane i, where they accumulate against the valve k till the pressure is sufficient to partially open the valve and allow it to discharge from the machine, while the lighter portions of the offal are drawn into the fan D, Figs. 1 and 6, situated in the upper part of the vacuum-chamber G, as shown, or in any other suitable place, and blown out into a dust-room or other place of deposit through an opening, n. o o', air-passages between shelves h and h³. At

the end of the first series of shelves h , h , in the shaking vacuum-blast separator C, is placed the revolving disintegrating cylindrical brush E, or its equivalent, Figs. 1 and 8, revolving in a concave, H, lined with wire-cloth, or otherwise roughening the concave, so as to more effectually detach the adhering fiber and dust from the granules of the middlings. The wire-cloth p (see Fig. 8) is extended to some distance beyond the solid concave backing to separate and arrest the force of the sheet of middlings as it leaves the brush and falls on shelves h^3 . The shaking separator C is suspended on inclined links q , q , (see Fig. 2,) which hang on eccentric pins in the side beams of the frame or other convenient places. This separator is driven by two eccentrics, r , r , one near either end of shaft J, (see Figs. 2 and 4,) connected by rods or bars K, K, arranged as near as may be in the direction of motion of the separator, the suspending-links causing the separator to vibrate in inclined arcs of circles, with an upward forward and a downward backward motion, which causes the middlings falling on the shelves to move forward. To more effectually clean the middlings, &c., we use the sieve F, set in a shaking box, L, and secured to the ends of the same, but resting on rubber or other springs s , s , which aid in the vibrations of the sieve. The rubber springs are notched into said end pieces. The sieve is fastened by screws at each end, which pass through rubber pads. To prevent the sieve from clogging, we use one or more rappers, t , t —one either side of the sieve—and which may be arranged to strike either on the top or bottom of the side pieces of the sieve to jar the same. They are attached to a shaft, w , extending across the separator, and moving with it, one end projecting out, and formed into a slotted crank-arm, u . This is attached by a pin to a slotted swinging adjustable arm, M, pivoted to the frame-work outside. This will be adjusted by a set-screw, v , so as to place the pin in any part of the slot in the crank-arm to control the vibrations, and thereby graduate the force of the strokes of the rappers on the sieve. The shaking sieve-box L is divided longitudinally in three compartments, x , x^1 , x^2 . The two latter have bottoms l , on which the sifted middlings are conveyed to openings, and from thence, by spouts, &c., to the stones for regrinding. There is an upper conducting-bottom, l' , l' , in each side division, having openings with slides y , y , Figs. 1, 2, and 5, for the purpose of cutting off and grading the sifted middlings, the coarser and more impure parts of which are discharged through the passages into the screw-conveyer N, N, and conveyed from thence into the elevator O, O, Figs. 2 and 4, from which they are discharged into the feed-shoe and returned to be reseparated. When either of the slides y , y are drawn, all the middlings falling through are discharged to be reground. The bran and other coarse stuff fall over the tail of the sieve. The middle division x of the shaking

box L is an inverted air-passage, which is between the division x^1 and x^2 and the inclined longitudinal slats z , z , and extending throughout the whole interior length of the box L. The object of this central air-passage, and the passages between the slats z , z , is to admit air under the sieve, which, being deflected partially downward and outward both ways, passes through the sifted middlings, with a gentle horizontal current, as they fall from the sieve, and carrying away fiber or light dust that may not have been taken out by the upper separators, up through the passages ff , into the vacuum-chamber G, and from thence into the fan-box, and from which they are blown out of the machine.

This shaking box and sieve-carrier L is moved as follows: It is suspended by screws or pins in the upper ends of inclined links P, P, which swing on pins in parallel bars Q, Q, which bars are, in turn, suspended by pins in links P', P', which are hung on pins in the back side of the bolsters R, R. These links P' are elongated downward, having a roller or cross-bar extending under the box L, and uniting them together. In or near the center of this cross-bar is a long rod or handle, S, projecting beyond the frame A, and resting in a notch in a beam of the frame-work, or other place, where it may be fastened at any point, and thus graduate the movement of the sieve-box, &c., giving it a greater or less curvilinear forward and upward movement, and vice versa backward. The object of this is to throw the middlings forward with more or less rapidity on the sieve to graduate the sifting. T, T are two connecting-bars, pivoted at one end to sieve-box L, and attached at the other end to an eccentric, r, on shaft J, operated by pulley U, which also operates the connecting-rod c, which moves the shaking shoe B by means of the bent crank b, as before explained. A belt runs from this pulley U to the fan-pulley V, and a belt, 4, runs from pulley W on fan-shaft to the brush-pulley X, and operates the same. The elevator is operated by a belt, Y, on a pulley on fan-shaft to a pulley on the elevator-shaft. A reel may be used in connection with this purifier or not, as may be desired.

The operation of the whole machine is as follows: The unpurified middlings are received either in the return-conveyer at the bottom of the machine and conveyed, along with the returns, into the elevator, and elevated to the feeding-shoe, or they may be received into the feeding-shoe direct from the bolt, and in either case discharged therefrom in a wide, thin sheet across the upper shelf of the first series of shelves in the shaking separator, from thence are carried forward by the combined action of the air-draft and shaking motion of the separator, and fall from one shelf to another, being at the same time subjected to the action of gentle currents of air as they fall and are shaken along on the shelves, by which means the most of the fiber and other light impurities not adhering tenaciously to the granules of middlings

are separated therefrom and carried forward and upward through the first series of bent air-passages into the exhaust-chamber G above, while the middlings pass along and fall onto the cylindrical brush, which whips them around in the disintegrating-concave, and discharges them through and beyond the concave wire screen, which extends beyond the solid concave bed, from which they fall, with diminished velocity, in a diffused shower, onto the first of the second series of shelves, with the previously-adhering fiber and dust disintegrated therefrom, so that the various air-currents to which they are subjected, in shaking along on and falling off from one shelf to another, will most effectually separate and carry the remaining light impurities away from the good middlings, up through the second series of bent shelves and converging air-passages into the exhaust-chamber G above, where the denser particles of offal from both series fall into the upper shelves, and are, by the combined action of the air-currents and the peculiar shaking motion of the separator, carried along and dropped from one shelf to another till they descend the inclined plane at the tail of the separator and pass out under the valve from the machine, while the purified middlings pass along from shelf to shelf and down the lower inclined plane *j*, from which they fall onto the head of the sieve, through which they pass, falling in a greatly-diffused and gentle manner therefrom, through the air-currents from the lower slats *z z*, onto the bottoms of the shaking box L, which propel them along, discharging the purest and best into a spout or other receptacle, to be conducted to the stones to be reground, the coarsest and most impure passing into the return-conveyer N, from which they enter the bottom of the return-elevator, and pass up and empty into the distributing feeding-shoe, along with the new middlings to be reseparated; while the dust and fiber separated therefrom by the air-currents below the sieve are drawn up through the side passages *ff*, between the sides *e e'* of the sieve and sieve-carrier L, and between the sides of the upper shaking separator, and are discharged into the exhaust-chamber G, from which the lightest part of it is drawn into the fan and discharged therefrom. The bran passes over the tail of the sieve.

The object of the shaking separator with the series of shelves is to carry the middlings forward and drop them, through several shortfalls, from shelf to shelf, so as to subject them, while being agitated by the shaking motion thereof, and falling from one to another with little velocity, to the action of numerous currents of air, which thereby more effectually separate all light impurities from the middlings, and carry them up into the exhaust-chamber, and also into the fan, as before stated; and, further, to convey the middlings from the head of the separator to the opposite end of the machine to discharge them onto the head of the sieve, which extends nearly or quite the

whole length of the machine; also, to arrest and carry forward to the place of discharge the heavy portions of offal, so that they may not lodge and clog the air-passages.

The sifted middlings are also subjected to the action of the air-currents through the central longitudinal slats *z z* in the compartments *x x' x''* as they fall from the sieve, and also while being shaken along on the bottoms *ll'* of the box L. They are also subjected to the action of air-currents while being shaken along on the sieve, which raises and carries any very light dust that may rise from the sieve up through the shelves in the separator, to the exhaust-chamber above.

There may be open inclined slats *z z* in one side of the box L, that carries the sieve, instead of in the center, as shown, admitting air to pass across under the sieve, and carry dust up, through a passage in the opposite side, into the exhaust-chamber.

It will be readily seen that, by these combinations and arrangements, the middlings are subject to the action of air-currents from the time they leave the distributing-shoe till their final exit from the machine in a perfect state.

The sieve is set level, so as to make a saving of height in the machine, and a simpler construction. The cloth on the sieve is coarser at the tail than at the head. The brush E is used solely to disintegrate the middlings, and not for any other purpose. The valve *k* has a flexible apron or bushing attached inside, and protruding downward beyond the valve itself, and beyond the incline *i* and outside of the opening. This is to prevent air from entering in as the offal is being discharged.

The valves *g g* perform three functions by their peculiar construction and combination with the walls *e e'*. They graduate the openings of the air-passages *ff*; also, close the opening between the walls *e* and the sides of the inverted cover of the vacuum-chamber G; also, from the inclination of the upper part, sheds the offal, over the inside *e'*, onto the shelves *h h'*.

We are aware that a stationary tapering feed-board is not new, but such is not our invention.

We claim—

1. The movable feeding and distributing shoe B, constructed with a tapering end, as described, to distribute the contents in a wide sheet, as herein set forth.

2. The movable feeding and distributing shoe B, having a corrugated bottom, and constructed as described, to deliver the contents in a wide sheet, in combination with a valve, *d*, for spreading the middlings, substantially as specified.

3. The double walls *e e'* and air-space *ff*, with valves or sliding gates *g g*, constructed and arranged substantially in the manner and for the purposes specified.

4. The shaking separator C, with the double walls *e e'*, air-space *ff*, and valve *g g*, the whole suspended on links *q q*, and operated by eccen-

tric bars K K and eccentric $r r$, on shaft J, in the manner and for the purpose specified.

5. In a moving separator, C, the series of shelves and bent partitions $h h^1 h^3 h^4$, and inclined planes $i j$, and air-spaces $m m' o o'$, as and for the purpose specified.

6. The combination of the movable separator C and shelves h and h^3 with the revolving disintegrating-brush E, concave H, and fan D, as and for the purpose specified.

7. The combination of the lengthened wire-cloth p with the cylindrical brush E and concave H, substantially as described, for the object set forth.

8. The shaft J, having eccentrics r and links K and T, connected to the shaking separator C, and vibrating sieve-box L, all constructed and combined so that the separator and sieve-box receive a simultaneous motion from the shaft, substantially as described.

9. The shaking sieve-box L, in combination with the links P P P' P', parallel bars Q Q, and lever S, arranged and operating substantially as and for the purpose specified.

10. In a movable box, L, the combination of the sieve F, the separating-slats z z, the longitudinal divisions $x x^1 x^2$, the bottoms $l l'$, and slides $y y$, all arranged and operating substantially as herein set forth.

11. The rappers t t, in combination with the slotted crank-arm u, set-screw v, and swinging adjustable arm M, substantially as described.

In witness whereof we have hereunto signed our names in the presence of two subscribing witnesses.

GEO. WALKER.
EDWIN WALKER.
